DESIGN FOR A BOOTLETTE

Beulah Hill, Los Angeles, Calif.

Application September 10, 1941, Serial No. 103,274

Term of patent 7 years

To all whom it may concern:

Be it known that I, Beulah Hill, a citizen of the United States, residing at Los Angeles, in the county of Los Angeles and State of California, have invented a new, original, and ornamental Design for Bootlettes, of which the following is a specification, reference being had to the accompanying drawing, forming a part thereof, and wherein

Figure 1 is a side elevational view of a bootlette, showing my new design.

Figure 2 is a frontal elevational view.

Figure 3 is a top plan view.

Figure 4 is a rear elevational view.

My design for a bootlette, as shown, is characterized by a body portion having a straight vertical lines, with a plain band at the top, a strap of less width than said band; a bottom edge comprising an undulating curve, an extended curved toe portion and a zipper in the front thereof.

I claim:

The ornamental design for a bootlette, as shown and described.

BEULAH HILL.
